Patented Sept. 1, 1908.

Application filed June 8, 1908. Serial No. 437,456. Term of patent 14 years.

To all whom it may concern:

Be it known that I, GARRY P. The figure is a side elevation of a bottle showing my new design, the distinguishing features of which are: the curved part 2,

above the curved part 3, but on a greater radius, whereby the outlines blend from the slightly conical part 4, to the cylindrical part 5; and the plain part 6, and ribs 7, and 8.
